PLAYER COMPANY, OF MILAN, ILLINOIS, A CORPORATION OF ILLINOIS.

PNEUMATIC ACTION FOR MUSICAL INSTRUMENTS.

1,033,217.

Specification of Letters Patent. Patented July 23, 1912.

Application filed September 21, 1908. Serial No. 454,099.

To all whom it may concern:

Be it known that I, EUGENE T. TURNER, a citizen of the United States, residing at Rock Island, in the county of Rock Island and State of Illinois, have invented certain new and useful Improvements in Pneumatic Actions for Musical Instruments, of which the following is a specification.

This invention relates to improvements in pneumatic actions for musical instruments in which the pneumatic action is controlled by a music sheet or record, each action being complete in itself whereby each of the piano actions will be controlled by an individual pneumatic action and which pneumatic actions are adapted to be supported by and have communication with a wind chest or trunk, and the primary object of the invention is to provide an improved means of attaching the pneumatic actions to the wind chest or trunk.

A further object is to provide an improved form of valve box or primary pneumatic, which is separate from the main pneumatic of each action, and improved means for securing the valve box to the wind trunk and the main pneumatic whereby the valve box may be readily and independently removed without interfering with any of the other parts of the pneumatic action or any of the adjacent actions.

A further object is to provide an improved device of this character which will be simple, durable and cheap in construction and effective and efficient in operation.

To the attainment of these ends and the accomplishment of other new and useful objects as will appear, the invention consists in the features of novelty in the construction, combination and arrangement of the several parts hereinafter more fully described and claimed and shown in the accompanying drawing, illustrating the embodiment of the invention and in which—

Figure 1 is a side elevation of an improved device of this character constructed in accordance with the principles of this invention attached to a wind chest or trunk and showing the latter in section. Fig. 2 is a detail elevation of the end of the valve box or primary pneumatic which stands adjacent the wall of the wind trunk. Fig. 3

is a left hand end elevation of Fig. 1 with the primary pneumatic removed. Fig. 4 is a side elevation of a modified form of the invention. Fig. 5 is a left hand end elevation of Fig. 4. Fig. 6 is a detail top plan view of the shoe for connecting the pneumatic action to the piano action. Fig. 7 is a sectional view taken on line 7—7 Fig. 1. Fig. 8 is a detail view similar to Fig. 1 showing the pneumatic case partly removed from its recess.

Referring more particularly to the drawing and in the present exemplification of the invention, the numeral 10 designates the wind chest or trunk from which the air is to be exhausted in any desired or well known manner. Supported by the chest 10, preferably by the lower side thereof is the main or striking pneumatic 11 which is secured to the chest preferably by gluing one of the members of the pneumatic 11 thereto and this member 12 projects beyond the front wall 13 of the wind chest for any desired or suitable distance. When the pneumatic 11 is secured to the wind chest the portion 14 thereof which projects beyond the wall 13 of the chest co-operates with said wall to form an acute angle or an angle less than a right angle.

A valve box or primary pneumatic 15 is provided with the necessary ports or passages and the usual controlling valves. This valve box 15 is preferably of a width substantially equal to the width of the projecting portion 14 of the member 12 of the pneumatic 11 and is of a height substantially equal to the height of the wind chest or trunk. The walls 16, 17 of the valve box are arranged at a right angle to each other and the valve box is adapted to rest upon the projecting portion 14 of the pneumatic so that the wall 17 thereof will engage said portion while the wall 16 will stand adjacent the wall 13 of the wind chest. The valve box 15 may be secured to the wind chest in any desired or suitable manner, preferably by means of a fastening device 18 such as a screw or the like, which is provided with a head 19. The valve box is provided with a recess 20 opening through the outer wall thereof and the fastening device 18 is adapted to pass through the wall

16 of the valve box so that the head 19 thereof will be seated within the recess 20, the extremity of the fastening device 18 entering the wall of the wind chest, so that 5 when the fastening device 18 is tightened to draw the valve box 15 against the wind chest, the projecting portion 14 of the pneumatic 11 will be forced slightly away from the chest 10 so that the acute angle formed 10 by such portion and the wall 13 of the chest will conform to the angle of the walls 16, 17, of the valve box, thereby forming a tight joint between the parts. If desired, suitable packing material 21 may 15 be disposed between the wall 16 of the valve box and the wall 13 of the chest to form a fluid tight joint. The valve box, in the exemplification of the invention shown in Figs. 1 to 3, is provided with a plurality of 20 apertures 22, 23, in the rear wall 16 thereof, which are adapted to register respectively with passages 24, 25, in the wind chest 10. The passage 24 has communication with the aperture 22 and also has communication 25 with the pneumatic 11 through an aperture 26 in the member 12 of the pneumatic while the aperture 23 communicates directly with the inside of the wind chest 10.

The pneumatic 11 is secured to the wind 30 chest so that the large end thereof will be disposed below the valve box 15 and toward the front of the piano or musical instrument and the smaller end of the pneumatic will be disposed adjacent the sticker 27 of the 35 piano action, which is supported from the flange rail by means of the link 28 in the ordinary and well known manner. The shoe 29 is provided for connecting the pneumatic action to the piano action. This shoe 40 29 is provided with a bifurcated extremity 30 having a reduced slotted portion 31 extending from the base of the bifurcation and into the body portion of the shoe so that the arms of the bifurcated portion may be 45 slightly separated without the danger of breaking the arms. This shoe 29 is attached to the sticker 27 by forcing the bifurcated portion 30 over the sticker preferably adjacent the bottom thereof and may be secured 50 thereto in any desired or suitable manner, preferably by means of glue. By providing the slot 31 in the shoe it will be apparent that the bifurcated extremity will serve as a clamp for holding the sleeve in position 55 until the glue sets. The opposite extremity of the shoe 29 is also bifurcated as at 32 and the extremities of the arms of the bifurcation are preferably rounded outwardly as at 33.

60 Secured to and depending from the movable member of the pneumatic 11 is a screw or bolt 34 which is preferably located at substantially the longitudinal center of the member, and this screw or bolt is provided 65 with a threaded extremity 35 adapted to

receive a nut or collar 36. The screw or bolt 34 is adapted to enter the bifurcation 32 in the shoe 29 when the main pneumatic 11 is placed in position and to readily pass out of the bifurcation to permit the action to be 70 readily and quickly removed without interfering with any of the other portions of the mechanism, the rounded portions 33 of the walls of the bifurcation serving to direct the member 34 into the bifurcation. This bolt or member 34 is of a length to permit the piano action to be operated by the piano keys through the medium of the capstan 37 in the usual manner, so as to provide a sufficient space between the top of the shoe 29 and the movable member of the pneumatic to permit the shoe to move under the influence of the capstan 37 without moving the movable member of the pneumatic, whereby the piano action may be operated 80 either by the pneumatic action or the keys whenever desired, so that the hammer 38 will strike the strings of the instrument to sound the notes. If desired a suitable washer 39 of felt or the like may be provided 85 between the nut or collar 36 and the adjacent portion of the shoe 29.

The valve box or primary pneumatic 15 may be connected to the tracker board of the instrument in the ordinary and well known 90 manner through the medium of a tubular member 40, which leads into the valve box and projects beyond one of the walls thereof and to which the respective flexible tubes leading from the tracker board may be connected.

In the form of the invention shown in Figs. 4 and 5 of the drawing, the aperture 23 has connection with the wind chest 10 through the wall 13 thereof and a passage 41 leads through the bottom or wall 17 of the valve box and has communication with the main pneumatic 11 through an opening 42 in the member 12 thereof and which opening is preferably located beyond the front wall 13 of the wind chest. In this exemplification of the invention additional packing 43 may be disposed between the wall 17 of the valve box and the member 12 of the main pneumatic.

With this improved construction it will be apparent that the valve box or primary pneumatic may be readily removed without detaching the main pneumatic and may as readily be replaced in position. When the valve box is secured in position, the portion 14 of the main pneumatic which projects beyond the front wall 13 of the wind chest, will yield sufficiently to conform to the wall 17 of the valve box without becoming detached from the wind chest.

In order that the invention might be fully understood, the details of the foregoing embodiment thereof have been thus described, but

What I claim as new is—

1. In a pneumatic action for musical instruments, the combination of a wind chest, a main pneumatic secured to the wind chest, 5 a controlling pneumatic for the main pneumatic, separate therefrom, and including a valve disposed to operate horizontally and transversely with relation to the main pneumatic, and means for independently and removably securing the controlling pneumatic in position. 10
2. In a pneumatic action for musical instruments, the combination of a wind chest, a main pneumatic secured to the wind chest, 15 a controlling pneumatic for the main pneumatic, separate therefrom, and including a valve disposed to operate horizontally and transversely with relation to the main pneumatic, and means for independently and removably securing the controlling pneumatic to the wind chest, said controlling pneumatic having direct communication with the wind chest and with the main pneumatic. 20
- 25 3. In a pneumatic action for musical instruments, the combination of a wind chest, a main pneumatic secured to the wind chest with a portion of the pneumatic projecting beyond one wall of the chest and coöperating with said wall to form an angle, a controlling pneumatic for the main pneumatic separate therefrom, and including a valve disposed to operate horizontally and transversely with relation to the main pneumatic, 30 said controlling pneumatic engaging the portion of the main pneumatic projecting beyond the wall of the chest, and also the said wall of the chest, and means for independently and removably securing the controlling pneumatic to the chest, said controlling pneumatic having direct communication with the main pneumatic and with the wind chest. 35
4. In a pneumatic action for musical instruments, the combination of a wind chest, a main pneumatic secured to the wind chest with a portion of the pneumatic projecting beyond one wall of the chest and coöperating with said wall to form an angle, a controlling pneumatic for the main pneumatic separate therefrom and including a valve disposed to operate horizontally, said controlling pneumatic engaging the portion of the main pneumatic projecting beyond the 45 wall of the chest, and also the said wall of the chest, means for independently and removably securing the controlling pneumatic to the chest, said controlling pneumatic having direct communication with the main pneumatic and with the wind chest, and packing material disposed between the co-operating faces of the parts through which the passages extend. 55
5. In a pneumatic action for musical instruments, the combination of a wind chest, 60
- a main pneumatic secured to the chest with a portion thereof projecting beyond one wall of the chest and coöperating therewith to form an angle, a controlling pneumatic for the main pneumatic including a valve box, two of the adjacent walls of the valve box coöperating to form an angle of a greater degree than the degree of the angle formed by the wall of the chest and the coöperating portion of the main pneumatic, and means for forcing the angle formed by the said walls of the valve box into the angle formed by the wall of the wind chest and the projecting coöperating portion of the main pneumatic, and for securing the valve box in position. 70
6. In a pneumatic action for musical instruments, the combination of a wind chest, a main pneumatic secured to the chest with a portion thereof projecting beyond one wall of the chest and coöperating therewith to form an angle, a controlling pneumatic for the main pneumatic including a valve box, two of the adjacent walls of the valve box coöperating to form an angle of a greater degree than the degree of the angle formed by the wall of the chest and the coöperating portion of the main pneumatic, and means for forcing the angle formed by the said walls of the valve box into the angle formed by the wall of the wind chest and the projecting coöperating portion of the main pneumatic, and for independently and removably securing the valve box to the wind chest. 75
- 80
7. In a pneumatic action for musical instruments, the combination of a wind chest, a main pneumatic secured thereto with a portion thereof projecting beyond one wall of the chest and coöperating therewith to form an angle, a controlling pneumatic for the main pneumatic including a valve box, two of the walls of the valve box coöperating to form an angle of a different degree than the degree of the angle formed by the main pneumatic and the wall of the wind chest, and means for removably and independently securing the valve box to the wind chest and for forcing the greater angle within the smaller angle to cause the two 90
- 95 said angles to coincide. 100
8. In a pneumatic action for musical instruments, the combination of a wind chest, a main pneumatic projecting beyond one wall of the chest and coöperating with the wall to form an angle, and a valve box, two adjacent walls of which coöperate to form an angle of greater degree than the normal degree of the first recited angle, the greater angle being forced into the smaller angle. 110
9. In a pneumatic action for musical instruments, the combination of a wind chest, a main pneumatic projecting beyond one wall of the chest and coöperating with the wall to form an angle, a valve box two ad- 115
- 120
- 125
- 130

jacent walls of which coöperate to form an angle of greater degree than the normal degree of the first recited angle, the greater angle being forced into the smaller angle,
5 and means securing the parts together.

In testimony whereof I have signed my name to this specification, in the presence

of two subscribing witnesses, on this 14 day of September A. D. 1908.

EUGENE T. TURNER.
